LIGHT ACTUATED DETECTOR FOR SHIFTING SHUTTLE BOX LOOMS

Richard G. Turner, Worcester, Mass., assignor to Crompton & Knowles Loom Works, Worcester, Mass., a corporation of Massachusetts

Application April 26, 1934, Serial No. 722,550

22 Claims. (Cl. 139—273)

This invention relates to improvements in weft detectors for shifting shuttle box looms and it is the general object of the invention to provide a light actuated detecting element on a loom of the type specified which is actuated or energized by a change in illumination of the detector when the supply of weft becomes substantially depleted.

In my co-pending application Serial No. 720,739 I have set forth and claimed in broad terms a weft detector actuated or energized by a beam of light and shown in connection with looms for changing shuttle, changing bobbin, and stopping upon exhaustion of weft. As shown in that application the weft detector is mounted in front of the lay and is controlled in part by lay motion. It is an important object of my present invention to adapt this general type of weft detector to the shifting shuttle box end of a loom and to provide for its control so that the detecting operation will take place in connection only with the shuttle to be detected.

In so-called pick and pick looms a set of shifting shuttle boxes is provided at each end of the lay to operate with several shuttles any one of which can be rendered active at will. In the operation of a loom of this kind it is frequently desirable in meeting the demands of a particular pattern to have two shuttles picked from the same end of the loom on successive beats of the lay. Furthermore, it is occasionally necessary for the boxes to move a distance greater than the distance between adjacent shuttle boxes, as for instance when the shuttle in box #1 is to be followed immediately by the shuttle in box #3. The shifting of the boxes will ordinarily occur while the lay is in its forward position and is completed either at or some time immediately prior to picking of the shuttle.

It is a further important object of my present invention to provide a timing control for the detector so that it can operate only at such times as the shuttle which is to be next picked has been placed opposite the race of the lay. If the box shift is to require an idle shuttle to move past the detecting position such movement will occur prior to the time that the control will permit the detector to indicate. In this way an idle exhausted shuttle will not be detected unless detection is desired.

It is a further object of my present invention to dispose the filament of the detector tube so that it can take full advantage of the beam of light directed toward it. In the present instance, the light is to be reflected from a surface carried by the bobbin and uncovered as weft depletion

approaches and the filament is preferably made so that it is parallel to the beam of light which is reflected from the bobbin.

It is a further object of the present invention to move the detector tube with the lay so that the distance between said tube and the energized surface will remain substantially constant.

The change in loom operation effected by the detector, as shown herein, is loom stoppage caused preferably with the depleted shuttle on the side 10 of the loom opposite the detector and with the lay in rear position. I do not wish to be limited, however, to this particular kind of loom control.

With these and other objects in view which will appear as the description proceeds, my invention resides in the combination and arrangement of parts hereinafter described and set forth in the claims.

In the accompanying drawings, wherein a convenient embodiment of my invention is set forth, 20

Fig. 1 is a vertical section through a shifting shuttle box loom having my invention applied thereto.

Fig. 2 is a view similar to a portion of Fig. 1 but showing the shuttle boxes and detector element on an enlarged scale, the boxes being in a different position.

Fig. 3 is a plan view looking in the direction of arrow 3, Fig. 2.

Fig. 4 is a vertical section on line 4—4 of Fig. 2, 30

Fig. 5 is a detail plan view in the direction of arrow 5, Fig. 1, and

Fig. 6 is part of the electric wiring used in connection with my invention.

Referring to the drawings, the loom frame 10 has a top or crank shaft 11 rotating once for each beat of the lay L and is connected by a gear 12 meshing with a second gear 13 on the bottom shaft 14. A picking arm 15 secured to the bottom shaft has picking balls 16 and 17, respectively, 40 which coat with a picking shoe 18 secured to the rocking picker shaft 19. The latter is pivotally supported on one of the loomsides and has upstanding therefrom an arm 20 which is connected in well-known manner to the picker stick 45 21. The latter is pivoted to the rocker foot 22 and at its upper end actuates a picker 23.

A set of shifting shuttle boxes B is mounted on the upper end of a box lifter rod 24 and carries in the present instance four cells to cooperate 50 with shuttles 25, 26, 27 and 28. The race plate 29 of the lay is shown herein as aligned with the top shuttle 25. A picker spindle 30 is secured to the lay and serves to guide the picker 23.

The connector 31 between the lay and the crank 55

- shaft 11 is the means by which the lay is reciprocated toward and from front position and it is to be understood that the box lifter rod is actuated to have its shifting movement with respect to the lay when the latter is in the forward half of its swing. This shifting movement may if desired be accomplished on a so-called Knowles head loom by means of a chain 32 connected to the bottom of the box lifter rod 24.
- 10 It is to be understood that the opposite end of the lay may be provided with a similar set of shifting boxes and that the two sets can move independently of each other by well-known mechanism not set forth herein.
- 15 As the invention is illustrated in connection with a loom which stops upon exhaustion of weft I show a shipper handle 35 connected at its lower end to a rod 36, the rear end 37 of which may be connected to shipping devices not shown herein but well understood. The relation of the parts is such that when the shipper handle is pulled forwardly the end 37 is moved rearwardly in order to start the loom, and when rod 36 is moved forwardly the loom stops.
- 20 A cam 38 on the top shaft coacts with cam lever 39 pivoted to fixed structure 40 and having an operating finger 41 which moves back and forth during loom operation. The exact timing of the finger can be controlled by angular adjustment of the cam 38 with respect to the top shaft. A push link 42 is pivoted at its rear end to a knock-off lever 43 and the lower end of the latter is connected to a forwardly extending rod 44 attached to the rod 36 as at 45, see Fig. 1. A
- 25 solenoid or other electro-magnetic device 50 has a core 51 connected to the link 42 and the parts are so related that when the device 50 is de-energized the link 42 will be in the low position shown in Fig. 1 beneath the path of movement of the actuating finger 41. When the device 50 is energized, however, its core acts to raise the link into the path of part 41 and the latter upon its subsequent backward motion will rock knock-off lever 43 in a clockwise direction to move the rod 44 forwardly and therefore rock the shipper handle rearwardly or to the right as viewed in Fig. 1 to stop the loom.
- 30 The devices thus far described are of known constructions and of themselves form no part of my present invention.
- 35 In carrying my present invention into effect I form each of the shuttles with a slot or port 60 and provide the corresponding binder 61 with a substantially similar slot 62. The shuttles carry bobbins 63 each having a metallic ferrule 64 which may have a highly reflective chromium plated surface. The bobbin may be provided with a bunch of reserve weft R which permits the shuttle to have a limited number of picks subsequent to indication of weft exhaustion. As the boxes shift one after another of the shuttles will assume the position shown by the top shuttle in Fig. 2. It is to be understood that the shuttle in the position of the top shuttle of that figure is opposite the race and therefore ready to be picked.
- 40 The detecting mechanism is located in a housing 70 having a partition 71 which forms a detecting compartment 72 and a light source compartment 73. In the latter I provide any convenient form of illuminant such as an incandescent lamp 74. It is to be understood that any source of light adequate for the purpose and shining at the desired times may be substituted for lamp 74. Housing 70 is carried by a bracket M on the lay.
- 45 75 In the other compartment 72 I provide the

photo-electric tube 75 which may have a plate 76 and a wire 77. The plate and wire are preferably horizontal and are therefore parallel to the ferrule in picking position.

The wiring connections are not set forth in detail herein since they may be substantially the same as shown in the aforesaid application, but I have indicated certain parts of the circuit in Fig. 6. Secured to the loom frame at the lower left hand part of Fig. 1 is the relay 88 which may be fed by power wires 81 and 82, respectively, and these wires also feed the lamp 74. Extending between the solenoid 50 and the relay 88 are two wires 83 and 84 which are connected to a switch designated generally at 85 in Fig. 1. This switch 15 has upper and lower prongs 86 and 87, respectively, which are normally so constructed as to spring apart to break the connection between wires 83 and 84. These last named wires are in the relay circuit so that the relay is normally 20 open and the solenoid circuit cannot be energized even though the photo-electric tube should send an impulse the ordinary effect of which would be to energize the relay.

Secured to the bottom shaft in timed relation 25 with respect to the picking arm 15 are insulated cam points 88 and 89, respectively, which are preferably located 180° apart and are so positioned with respect to the lower electrode 87 as to raise the latter against the upper electrode 86 30 when the parts are in position shown in Fig. 1. At other times the electrodes are unaffected by the cams and are out of contact.

In operation, the boxes will shift according to the requirements of the pattern as already described and so long as sufficient weft is present in all of the shuttles their respective ferrules will be covered and no light can be directed toward the photo-electric tube. When one of the bobbins becomes substantially depleted, however, as 40 shown in Fig. 3, light starting from the source 74 will be directed toward the ferrule 64 and reflected forwardly therefrom to the photo-electric tube 75, energizing the latter. It is considered sufficient for the purpose of the present description to state that energization of the photo-electric tube will cause current to flow in winding 90 of the relay. The full circuit of the relay is not shown, but is well known. The cams 88 and 89 are so related to the electrodes of the switch that 50 the latter is closed preferably a short time before the loom picks, which means that the shuttle which is exhausted will be practically at rest with respect to the lay at this time. The condition depicted in Fig. 3 can therefore exist and 55 current will flow through the switch to the relay.

Having particular reference to Fig. 6, the winding 90 of the relay, when energized, will attract the armature 91 so that a circuit will be established as follows: wire 81, wire 92, contact 93, 60 armature 91, wire 83, prongs 86 and 87, wire 84, device 50 and wire 96 back to the opposite side of the line or wire 82. Upon closure of this circuit the link 42 will be raised in the path of the finger 41 and as previously described will result 65 in loom stoppage. As soon as one or the other of the cam points 88 or 89 moves out of operative position with respect to switch the circuit of the solenoid will be broken and the parts will return to their normal position.

It should be noted that the shifting of the boxes which normally comes between boxing of the shuttle and picking while the lay is in the forward part of its stroke will have no effect on the relay or the solenoid, since these parts are held against 70 75

operation by the switch 85 until the shifting boxes come practically to rest with respect to the lay.

If desired those parts of the lay and shuttle boxes which lie in the path of light which can be directed toward the photo-electric tube may be coated with a dull black paint or the like. The lay end will ordinarily have a slot 100 for the picker and the boxes will be slotted as at 101 so that any light which is directed through these slots 100 and 101 will not have opportunity to return to the photo-electric tube with a sufficient intensity to produce an exciting current. The spindle 30 will be far enough behind the axis of the shuttle so that any light which it may reflect can be kept well below the amount required to give an indication through the photo-electric tube. Since the intensity of the illumination varies inversely as the square of the distance traversed by the beam it will be understood that no part at a substantial distance behind the ferrule will be able to reflect a sufficient amount of light to give an indication.

Means not specifically shown herein but set forth in my aforesaid application can be used to regulate the circuit so that the amount of current set up by light reflected from the ferrules will be the minimum and any less current will be insufficient. The time during which the active shuttle is in position to reflect light toward the photo-electric tube will be small, but sufficient nevertheless to actuate the cell 75.

It is to be understood that the circuits used in connection with the photo-electric detector includes several branches any of which may be broken by a switch similar to that shown at 85 for the purpose of preventing the relaying of current to the solenoid at an improper time and I do not wish to be limited to the particular means set forth herein for accomplishing this general result.

I have found that different colored yarns have different powers of reflecting light toward the photo-electric tube. In drop box looms it is customary to have each shuttle carry weft distinctive from that of the other shuttles and this will ordinarily result in a variable amount of light being reflected toward the detector. By means of a photometer which itself uses a photo-electric tube and indicates by an electrically actuated hand passing over a dial I have found that red weft gives a reading of 60 units, white cotton has a reading of 100 units, slack twist white rayon reads 120 units, while the uncovered chromium ferrule gives a reading of 150 units. It would appear therefore that a ferrule can be made which will reflect appreciably more light than the whitest yarns with which I experimented.

It is to be understood that the adjustment of the sensitiveness of the detector tube and the parts of the circuit connected to it will be such as to actuate or energize the control circuits when the light reflected lies above the highest amount which can be gotten from the most reflective of the yarn employed.

From the foregoing it will be seen that I have provided a very delicate weft detector to be used in connection with shifting shuttle boxes. It will further be seen that the detector parts are carried by the lay and the longitudinal axes of the sensitive elements within the photo-electric tube are substantially parallel to the ferrules on the bobbins. It will also be seen that I have provided means for interrupting a control circuit at all times except those when it is proper that such a circuit should be closed.

As suggested in Figs. 2 and 4, the filament 77 and plate 76 are parallel to the ferrule, hence the light reflected from the latter will in effect lie in a plane and will fall on the whole length of the sensitive parts at once to give greatest effect.

Having thus described my invention it will be seen that changes and modifications may be made therein by those skilled in the art without departing from the spirit and scope of the invention and I do not wish to be limited to the details herein disclosed, but what I claim is:

1. In a loom, a photo-electric tube, means to initiate a change in loom operation when the illumination of the photo-electric tube is changed, shifting shuttle boxes, and means carried by each shuttle box and dependent upon weft exhaustion to effect a change in illumination of the detector.

2. In a loom, shifting shuttle boxes carrying shuttles and movable with respect to the lay to place each box in picking position, a light responsive detector to be actuated to effect a change in loom operation upon a change of illumination, and means carried by each shuttle effective when weft exhaustion occurs in the shuttle to change the illumination of the detector.

3. In a loom, shifting shuttle boxes carrying shuttles and movable with respect to the lay to place each box in picking position, a light responsive detector to effect a change in loom operation when the illumination thereof is altered, and means carried by each shuttle operative when weft exhaustion occurs in the shuttle to effect a change in illumination of the detector at a time immediately preceding picking of the exhausted shuttle.

4. In a loom, shifting shuttle boxes carrying shuttles and movable with respect to the lay to place each box in picking position, a light responsive detector to effect a change in loom operation when the illumination thereof is altered, means in each shuttle box to direct an actuating beam of light toward the detector to change the illumination thereof, and means to cause said change of illumination just prior to picking of an exhausted shuttle.

5. In a loom, a set of shifting shuttle boxes each containing a supply of weft, a weft detector effective when subjected to a change of illumination to bring about a change in the operation of the loom, and means carried by each of the shuttle boxes effective when the supply of weft therein is depleted to change the illumination of the detector.

6. In a loom, shifting shuttle boxes containing shuttles with weft supplies, a lay supporting the shifting boxes, means to pick a shuttle from one of the boxes when the lay has reached a predetermined point in its backward movement, a detector responsive to a change in illumination thereof to effect a change in loom operation, means carried by each shuttle box effective when weft exhaustion occurs therein to create a condition preparatory to changing the detector illumination, and means dependent upon existence of the condition to effect the change in detector illumination when the lay reaches the given point in its backward stroke.

7. In a loom, shifting shuttle boxes each having a shuttle supplied with weft, a lay, means to shift the boxes with respect to the lay, a detector responsive to a change in illumination thereof to initiate a change in loom operation, means carried by the shuttle of each shuttle box effective upon depletion of weft to prepare to change the 75
